UNITED STATES PATENT OFFICE.

JOHN BENNICI, OF CHICAGO, ILLINOIS, ASSIGNOR TO EAGLE WOOD TURNING COMPANY, OF CHICAGO, ILLINOIS.

DESIGN FOR A LAMP SHADE OR GLOBE.

56,689.

Specification for Design.

Patented Nov. 30, 1920.

Application filed May 24, 1920. Serial No. 383,955. Term of patent 3½ years.

To all whom it may concern:

Be it known that I, JOHN BENNICI, a citizen of the United States, and a resident of the city of Chicago, county of Cook, and State of Illinois, have invented a new, original, and ornamental Design for a Lamp Shade or Globe, of which the following is a specification, reference being had to the accompanying drawings, forming a part thereof, and in which—

Figure 1, is a side elevational view of a

lamp shade or globe embodying my new design, and

Fig. 2, is a top plan view of the design.

I claim:

The ornamental design for a lamp shade or globe, as shown.

Signed at Chicago, in the county of Cook and State of Illinois, this 19th day of May, 1920.

JOHN BENNICI.
